(57) **CLAIM**

The ornamental design for a set of toothbrush bristles with valley and wedge, as shown and described.

DESCRIPTION

FIG. 1 is a perspective view of the set of toothbrush bristles with valley and wedge of the present invention showing the brush head in dotted lines;

FIG. 2 is a left side view thereof;

FIG. 3 is a right side view thereof;

FIG. 4 is a top view thereof;

FIG. 5 is a bottom view thereof;

FIG. 6 is a front view; and,

FIG. 7 is a rear view thereof.

The dotted lines in FIGS. 1–7 are intended to show the brush head as environment and do not represent claimed subject matter
